(57) **CLAIM**

The ornamental design for an aircraft passenger seat, as
shown and described.

DESCRIPTION

FIG. 1 is a front perspective view of an aircraft passenger seat
showing our new design;

FIG. 2 is a front perspective view thereof;

FIG. 3 is a back perspective view thereof;

FIG. 4 is a front view thereof;

FIG. 5 is a back view thereof;

FIG. 6 is a top view thereof;

FIG. 7 is a bottom view thereof;

FIG. 8 is a first side view thereof; and,

FIG. 9 is a second side view thereof.

The even length broken lines illustrate structure and environment
that form no part of the claimed design. The single long
dash and single short dot broken lines represent a break line
illustrating bounds of the claimed design and forming part
thereof.
